UNITED STATES PATENT OFFICE.

HAROLD S. DAVIS, OF PITTSBURGH, PENNSYLVANIA, ASSIGNOR TO TEXAS GULF SULPHUR COMPANY, OF NEW YORK, N. Y., A CORPORATION OF TEXAS.

BURNING SULPHUR.

Application filed January 21, 1922. Serial No. 530,780.

To all whom it may concern:

Be it known that I, HAROLD S. DAVIS, a citizen of the Dominion of Canada, residing at Pittsburgh, Allegheny County, Pennsylvania, have invented a new and useful improvement in Burning Sulphur, of which the following is a full, clear, and exact description, reference being had to the accompanying drawings, forming part of this specification.

The present invention relates to burning sulphur and more particularly to a method and apparatus for burning crude sulphur containing impurities, such as traces of oil, which would otherwise render it not free burning.

Pure sulphur is free burning. However, the presence of certain organic impurities, particularly traces of petroleum which occur in the crude sulphur obtained from the deposits in the Gulf States of the United States, prevents such sulphur from being free burning. After ignition of the oil-containing sulphur, a film of carbonaceous material or asphalt spreads over the surface, and eventually extinguishes the flame, although the sulphur is only partially consumed. The oil reacts with the sulphur and forms the thin film of asphaltic material which spreads over the surface. The ignition temperature of this film is so much higher than that of the sulphur or the temperature developed during the burning of the sulphur, that the film is not ignited, and consequently, the whole flame is extinguished. Traces of oil amounting to only 1% or .2% are sufficient to render the sulphur not free burning. It has therefore heretofore been generally regarded as impossible to burn this oil-contaminated sulphur in an ordinary pan burner, and even in special devices, such as the rotary or cascade burners, the combustion of oil-contaminated sulphur presents some difficulties.

I have discovered that certain materials have a peculiar accelerating effect on the burning of sulphur and may be used to render the oil-contaminated sulphur free burning. Among the materials which I have, up to the present time, been able to investigate and have found to have this effect, are asbestos, magnesia and certain types of porous

brick, such as the heat-insulating brick known to the trade as "nonpareil" brick. Other materials, such as magnesium carbonate, infusorial earth and fuller's earth, possess the same property, but to a less degree. These materials are capable of absorbing and apparently exert a wick-like action on the melted sulphur. The fibrous structure of some of the materials, such as asbestos and magnesia, apparently greatly assist in this wick-like absorptive action on the sulphur. They are also poor heat conductors, so that the heat generated at the burning surface is not conducted away rapidly enough to reduce the temperature below the ignition point. These materials also appear to have some surface or catalytic action in accelerating the combustion of the sulphur. The materials are preferably incombustible.

I have found that if the sulphur is placed in a vessel made of or lined with one of these combustion-accelerating materials, the sulphur is rendered free burning. Instead of putting the material in a vessel lined with such material, I have also put pieces of the material in oil-contaminated sulphur and burned it in an ordinary earthenware dish. For example, if pieces of asbestos or magnesia insulation are added, the flame will continue around them until the sulphur is practically all burned.

In the drawings:

Figure 1 is a plan view of a pan burner embodying the invention.

Figure 2 is a vertical section along the line II-II of Figure 1;

Figure 3 is a view showing the invention applied to a cascade burner; and

Figure 4 is a view showing the invention applied to a rotary burner.

Referring to Figures 1 and 2, the burner consists of a sheet 2 of sulphur combustion-accelerating material, preferably asbestos. This sheet is formed into a pan-like shape to hold the sulphur in a pool as it melts. It is mounted on suitable legs 3, so that the air has access both above and below the pan. The crude sulphur 4 is preferably piled around the edges of the burner with some sulphur in the middle. The combustion of the sulphur is started preferably at the middle of the pan by a hot iron or by a

piece of paper or in any other way. As the sulphur burns, it melts and runs down forming a pool 5 in the middle of the pan. Soon after the sulphur begins to burn, the 5 asphaltic film will appear, but the sulphur will continue free burning where the burning surface is close to the asbestos. As the pool in the center of the pan increases in depth, the asphaltic film may temporarily 10 stop combustion on the deeper parts of the pool. However, combustion continues actively around the edges of the pool. Meanwhile, the sulphur soaks through the asbestos sheet and combustion starts on the lower 15 side. The sulphur does not drip from the bottom, but is apparently held by capillary action, much the same as oil is held in the wick of an ordinary kerosene lamp. The combustion proceeds briskly both above and 20 below, leaving finally a light ash remaining in the asbestos pan, which can be readily shaken out before the next lot of sulphur is to be burned. If desired, the asbestos pan may be strengthened mechanically by 25 ribs or a netting of aluminum or other material which is not attacked by the burning sulphur.

The invention may also be applied to the usual form of cascade sulphur burners. A 30 cascade burner comprises an outer casing 10 having holes 11, for the admission of the air, and an outlet 12 to conduct off the sulphur dioxide fumes. Across the inside of the casing 10 are placed a number of trays 35 13, upon which the sulphur is burned. The unmelted sulphur is placed upon the top tray and as it melts runs down through the openings 14 to the lower trays. The openings 14 are staggered. The usual practice 40 has been to make the trays of metal, relying upon the agitation of the dripping sulphur and the heat transmitted from one tray to another to keep up the combustion. I have found, however, that if the trays 13 45 be made of a sulphur combustion-accelerating material, such as asbestos, the sulphur can be burned more rapidly and completely than with metal trays.

In Figure 4, I have illustrated the application of the invention to a rotary burner. 50 The rotary burners are used in establishments where the amount of sulphur used warrants the expense of installing and maintaining them. A rotary burner consists of a horizontally mounted rotary drum 20, having air inlets 21 and an outlet 22 for sulphur dioxide gas. The drum is continuously rotated by gearing indicated at 55 23. Sulphur is generally charged into the end 24 of the drum. The melted sulphur forms a pool in the bottom of the drum. The continuing rotation of the drum agitates this pool and the rising side of the drum exposes a fresh surface freed from 60 the flame-deadening asphaltic film. I have 65

improved the rotary type of burner by lining it with a sulphur combustion-accelerating material, preferably asbestos. In the drawing, this lining is indicated by the reference numeral 25.

While I have described the invention and its practical embodiment as best known to me at the present time and from the investigations which I have so far been able to carry out, it is to be understood that I 70 do not intend to limit the invention to the specific materials which I have so far been able to investigate, as other specific sulphur-accelerating materials having the characteristics of the materials already investigated may be found on further investigation. The present invention is therefore not limited to the specific steps or materials herein disclosed, but may be otherwise embodied within the scope of the following 75 claims.

I claim:

1. The improvement in the burning of sulphur which comprises maintaining the sulphur freely burning by associating with the sulphur a sulphur combustion-accelerating material.
2. The improvement in the burning of sulphur which comprises maintaining the sulphur freely burning by associating with the sulphur a material porous to melted sulphur.
3. The improvement in the burning of sulphur which comprises maintaining the sulphur freely burning by associating with the sulphur a material which has a wick-like absorption for melted sulphur.
4. The improvement in the burning of sulphur which comprises maintaining the sulphur freely burning by associating with the sulphur a poor heat conducting material which has a wick-like absorption for melted sulphur.
5. The improvement in the burning of sulphur which comprises maintaining the sulphur freely burning by associating with the sulphur a material having a combustion accelerating surface or catalytic action on the sulphur.
6. The improvement in the burning of sulphur which comprises maintaining the sulphur freely burning by associating with the sulphur a non-combustible material which has a wick-like absorption for melted sulphur.
7. The improvement in the burning of sulphur which comprises maintaining the sulphur freely burning by associating with the sulphur a non-combustible mineral fibrous material.
8. A sulphur burner comprising a surface of sulphur-combustion-accelerating material, substantially as described.
9. A sulphur burner comprising a poor heat-conducting surface which is porous to melted sulphur, substantially as described.

10. A sulphur burner comprising a surface which has a wick-like absorption for melted sulphur, substantially as described.
11. A sulphur burner comprising a poor 5 heat-conducting porous surface which has a wick-like attraction for sulphur, substantially as described.
12. A sulphur burner comprising a fibrous incombustible melted sulphur-absorbing ma- 10 terial, substantially as described.
13. A sulphur burner comprising a pan of sulphur combustion-accelerating material, substantially as described.
14. A sulphur burner comprising an as- 15 bestos pan, substantially as described.
15. A sulphur burner comprising a sheet of incombustible porous material for holding the sulphur and having its lower surface exposed to the air to permit combustion of sulphur soaking through the sheet, substan- 20 tially as described.
16. A sulphur burner comprising a sheet of asbestos having its lower surface exposed to the air to permit combustion of the sulphur soaking through the sheet, substan- 25 tially as described.

In testimony whereof I have hereunto set my hand.

HAROLD S. DAVIS.
